UNITED STATES PATENT OFFICE.

PAUL CORNIÈRE, OF CLICHY, FRANCE, ASSIGNOR TO SOCIETE DE MECANIQUE NOUVELLE, OF PARIS, FRANCE.

STARTING DEVICE FOR INTERNAL-COMBUSTION ENGINES.

Application filed August 10, 1922. Serial No. 580,993.

To all whom it may concern:

Be it known that I, PAUL CORNIÈRE, a citizen of France, and a resident of Clichy (Seine), France, have invented certain new and useful Improvements in Starting Devices for Internal-Combustion Engines, which is fully set forth in the following specification.

The invention relates to starting device of internal combustion engines and consists in providing a small auxiliary cylinder wherein the piston is driven in one direction by an explosive mixture and returned to its initial position by a spring. The piston rod is formed with a rack which is so connected to the engine shaft that the latter is rotated on the power stroke of the piston.

The invention further consists in providing means for producing an explosive mixture and for injecting the same as soon as produced, into the engine cylinder, means for igniting the mixture in the cylinder being also provided. The burnt products of combustion are exhausted, at the end of the power stroke of the piston, through a port in the piston head, said port communicating with a passage in the piston rod that communicates with the cylinder below the piston. A valve controlling the port is operated automatically by the movement of the piston to open said port at the end of the power stroke and to close the same upon the return of the piston to its initial position.

The following description, together with the accompanying drawings which are given by way of example, sets forth this invention:

Fig. 1 shows in axial section and partly in external view, one form of construction of said device. Figs. 2 and 3 relate to a modified form. Fig. 2 being an axial section and Fig. 3 a section on the line 2-2 of Fig. 2.

The device, Fig. 1, comprises a small auxiliary cylinder *a* containing a piston *b* whose rod *b*¹ is formed with a rack at *b*² which engages pinion *c* coaxial with driving shaft *d*, which is to be started; pinion *c* is provided with the pawls *c*¹ co-operating with a ratchet wheel *d*¹ keyed to the driving shaft so as to actuate it in only one sense of rotation of pinion *c*, i. e. for the movement of auxiliary piston *b* in only one sense (for the power stroke or to the left).

One can deliver into the explosion chamber of auxiliary cylinder *a* an adequate charge of explosive mixture by a hand pump

e which connects at one end by the conduit *e*¹ with said explosion chamber and at the other end by the conduit *e*² to a reservoir *e*³ containing said mixture. A cock or check-valve *e*⁴ is mounted on the conduit *e*² to prevent said mixture from passing into the pump *e* except during the suction stroke of the pump; a check valve *e*⁵ is mounted on the conduit *e*¹ to prevent the mixture which is delivered into the explosion chamber of cylinder *a* from returning into the pump *e*. A spark plug *a*¹ which is mounted in a suitable manner in the cylinder head *a*² of the cylinder *a* and is connected to a magneto *e*⁶ of the plunger type, will afford one, or two sparks at the proper moment in the explosive mixture which is delivered by the pump *e* into cylinder *a*, in order to ignite this mixture.

The piston *b* carries a valve *b*³ whose stem *b*⁴ passing through an axial passage *b*⁵ in the piston rod *b*¹ carries the tappets *f* *f*¹; a lengthwise groove *b*⁶ formed in the thickness of the piston rod *b*¹ connects the axial passage *b*⁵ of said rod with the interior of cylinder *a*.

During the power stroke, the piston *b* communicates, through the rack *b*², pinion *c* and pawls *c*¹, an impulse to the shaft *d*; when the piston reaches the end of the stroke, (towards the left), the tappet *f* on rod *b*⁴ of the valve *b*³ makes contact with a finger, tenon or the like carried at the end *a*³ of the cylinder and extending through the slot *b*⁶ of the passage *b*⁵, thereby opening the valve *b*³. When the piston moves to the right, under the action of its return spring *b*⁷, the burnt gas escapes from the explosion chamber through valve *b*³ which is lifted from its seat, through the axial passages *b*⁵ and slot *b*⁶ and into the interior of the cylinder behind piston *b* and thence to the atmosphere through the holes *a*⁴ provided in the end of the cylinder. At the end of the return stroke of the piston (position shown in the figure) the tappet *f* acts upon another tappet *f*¹ on the valve stem and closes valve *b*³.

The auxiliary piston is thus ready to give a new power movement to shaft *d*, should the first one not have been effected sufficiently to perform the starting.

In the form of construction shown in Figs. 2 and 3, the rod *b*¹ of piston *b* of the auxiliary cylinder *a* carries valve *b*³; a coiled spring *b*⁸, mounted within the piston rod *b*¹

2
 between a shoulder b^9 on the piston rod and a collar b^{10} of the valve stem b^4 , tends constantly to lift the valve b^3 from its seat. But said valve b^3 is on the other hand acted upon by a spring f having spirals of a variable diameter disposed between said valve b^3 and the head a^2 of the auxiliary cylinder. When the piston b is at the end of the stroke towards the interior under the action of the 10 return spring b^7 , the spring f which is compressed between the cylinder head d^2 and the valve b^3 has a higher tension than the spring b^8 , so that valve b^3 remains closed. When piston b is moved forward by the explosion 15 of the mixture carburetted between the head a^2 of the cylinder and the piston b , the tension of spring f gradually diminishes until it becomes smaller than that of spring b^8 , when the piston has almost reached the end of the 20 outward stroke; at this moment, valve b^3 is lifted by spring b^8 , and the burnt gas escapes from the explosion chamber below the valve b^3 and through the hollow piston rod b^1 , to the exterior. The piston b is now brought 25 to the end of its stroke towards the interior by the return spring b^7 whose tension is greater than that of the spring f , which is compressed and closes valve b^3 .

The explosive mixture is sent at the proper 30 time into the auxiliary cylinder by a hand pump g surrounded by a gasoline reservoir h provided with a filling plug h^2 . By operating the piston g^1 of pump g , a certain vacuum is produced upon the fuel in said reservoir 35 which is connected to said pump by a nozzle h^6 and a tube h^5 . On the wall of said reservoir is provided an air inlet hole h^3 above the level of the liquid and of suitable cross-section, it being adjustable and about 5 hundredths of a millimeter in diameter and permitting the regulation of the quantity of 40 gasoline supplied to the nozzle h^6 , this quantity of gasoline being the same as the quantity of air entering the reservoir through the nozzle h^3 .

During the delivery stroke of the piston g^1 of pump g , the latter sends a certain amount of fuel through the tube h^8 which connects with the explosion chamber of the 50 auxiliary cylinder a ; said fuel which is atomized and mixed with air is thus sent into said explosion chamber wherein it is ignited by one or more sparks produced by spark plug a^1 mounted in cylinder head a^2 and connected to a magneto e^6 which is preferably driven by a pinion e^7 engaging a gear wheel having a square fit upon the rod of pump g ; in these conditions the rod is operated to pump when it is pushed, then to drive 55 the magneto for the starting, when it is rotated. A stop valve g^2 of ball type prevents gas from returning into the pump g and gasoline reservoir h during the explosion of the mixture in the auxiliary cylinder a .

60 During the outward stroke caused by ex-

plosion in the auxiliary cylinder a , see Figs. 2 and 3 the piston b acts on shaft d of the engine which is to be started, by means of the following device. The rack b^2 formed in the rod b^1 of piston, is engaged with a 70 pinion i keyed to an intermediate shaft i^1 journaled in the end a^3 of the auxiliary cylinder; at the periphery of shaft i^1 is formed a helical groove i^2 wherein is engaged a stud j^1 of a jaw coupling sleeve j mounted on the 75 shaft i^1 and cooperating with a like sleeve d^1 on the engine shaft d . During the power stroke of the piston b , the rack b^2 rotates shaft i^1 in the direction of the arrow, Fig. 2 thereby moving sleeve j to the left, through the stud j^1 engaging groove i^2 , and causes it to engage the sleeve d^1 , i. e., to actuate shaft d ; when the piston rises under the effect of its return spring b^7 , the shaft i^1 turns in contrary sense and the sleeve j moves to the 80 right upon said shaft, whereby it is released from sleeve d^1 and ceases to actuate the shaft d .

It is obvious that the embodiments hereinbefore described are susceptible of all desired modifications without departing from the principle of the invention.

What I claim is:

1. A device for starting internal combustion engines, comprising an auxiliary cylinder, a piston disposed in the latter, a pump for supplying an explosive mixture to the cylinder, a spark plug disposed in said cylinder, a magneto for producing a spark at the plug, a rack formed upon the piston rod, a pinion co-operating with said rack, a mechanical connection between the said pinion and the crankshaft of the engine, and automatic means for returning the piston of the auxiliary cylinder to the initial position after the down stroke of the same.

2. A device for starting internal combustion engines, comprising an auxiliary cylinder, a piston disposed in the latter, a tubular rod secured to said piston, an exhaust valve mounted within said rod, a coiled spring disposed within the piston rod for lifting said valve, and a spring mounted between the top of the valve body and the end of the cylinder whereby said valve is held closed when the piston is in its initial position while the valve is permitted to open when the piston descends, a hand pump for supplying an explosive mixture to the cylinder, means for effecting the ignition of the explosive mixture at will, a rack formed upon the piston rod, a pinion co-operating with said rack, a mechanical connection between said pinion and the crankshaft of the engine, and a spring disposed between the piston and the lower end of the cylinder whereby said piston is returned to the initial position.

3. A device for starting internal combustion engines, comprising an auxiliary cylin-

der, a piston in the latter, a fuel reservoir, a passage connecting said reservoir with the auxiliary cylinder, a nozzle disposed within said passage, a hand pump delivering into 5 said passage above the said nozzle, whereby an explosive mixture is supplied to said auxiliary cylinder by the movement of the said hand pump, a spark plug in the auxiliary cylinder, a magneto for producing a 10 spark at the spark plug, a mechanical connection between the shaft of the magneto and the rod of the hand pump whereby the rotation of the rod of the pump will effect the rotation of the magneto, and a mechanical connection between the rod of the auxiliary piston and the engine shaft.

4. A device for starting internal combustion engines, comprising an auxiliary cylinder, a piston in the latter, means for supplying 20 an explosive mixture to said cylinder,

means for igniting the mixture, a piston rod having a rack formed thereon, a pinion co-operating with said rack, a shaft on which said pinion is mounted, a helical groove formed in said shaft, a coupling sleeve on 25 the latter, a stud on said sleeve co-operating with the helical groove whereby said coupling sleeve is caused to slide and to rotate upon the rotation of the shaft, a sleeve mounted upon the shaft of the internal combustion engine and co-operating with said coupling sleeve whereby the rod of the auxiliary piston is connected with the engine shaft in only one direction of movement of the auxiliary piston, and means for automatically returning the piston to its initial 30 position.

In testimony whereof I have signed this specification.

PAUL CORNIÈRE.
